APPARATUS FOR THREADING TOBACCO LEAVES

Paul Muller, Neuf Brisach, France

Application July 20, 1935, Serial No. 32,409
In France July 25, 1934

5 Claims. (Cl. 131—21)

The present invention has for object a device for threading tobacco leaves upon a string for the purpose of drying said leaves. Apparatus for threading tobacco leaves are known in which the leaves are juxtaposed upon a work table and placed separately in supporting means which hold them fixed so as to permit the passage of the threading needle through the stems.

These threading apparatus present the drawback that the threading needle is formed as a flat body, such as a steel ribbon, wound upon a driving drum, or as a blade having rack teeth at one edge meshing with gears for the purpose of reciprocating the blade. Another drawback consists in that no means are provided for automatically securing the accurate location of the leaves so that they may be perforated exactly in the central part of the stem by the passage of the needle. Moreover, the perforation produced by such needles is oblong and may cause a splitting up of the stem in the direction of the fibres.

The threading apparatus, object of the present invention, eliminates the aforesaid drawbacks by using a needle of circular section and supports which suit the size of the tobacco stems and are adapted to be automatically adjusted so that the stems are duly centered with respect to the path of the needle.

In the accompanying drawing there is illustrated by way of example, a form of embodiment of such threading apparatus.

Fig. 1 is a plan view of the apparatus;

Fig. 2 is a vertical section thereof on line 2—2 of Fig. 1 but on larger scale and showing a support holding a tobacco leaf.

Fig. 3 is a front view of said support showing also the needle with the string.

Fig. 4 illustrates a detail of the drum driving the needle and seen in section on line A—B—C of Fig. 1.

In these drawings, *a* designates the work table (Fig. 1) upon which are mounted the supports *b* holding the tobacco leaves *c* and a drum *d* for moving the needle *e* (Fig. 1). The needle *e* is formed by a steel wire the end of which has a notch *e*₁ to be engaged by the string *f* (Fig. 3). The wire is wound inside the drum *d* (Figs. 1 and 4) the entrance of which has an offset guide *g* (Fig. 4) so as to cause the wire to wind in juxtaposed turns. For reciprocating the needle *e*, the crank handle *h* (Fig. 1) fixed to the drum *d* should be rotated. Due to the fact that the turns of wire *e* are enclosed within the drum *d* (Fig. 4) the unwinding and rewinding are performed without sliding and under the most ef-

ficient conditions. The needle *e* is guided through the supports *b* in apertures or notches *i* (Fig. 2). Each support moreover is fitted with a blade spring *k* (Fig. 3). The stem of the tobacco leaf is thus held between this blade spring and the upright support.

For the purpose of putting the stem in accurate position in front of the aperture *i* (Fig. 2) for the passage of the needle *e*, the support is provided in the other direction with two other springs *l* and *m*. The spring *l* forms a bearing for the stems and its movement is limited by the bar *n*. The upper spring *m* is pivotally mounted upon a shaft *o* and is loaded with a counterweight *p*. The latter springs are generally united in a single element mounted upon a common shaft and provided with a single counterweight (Fig. 1). For placing the tobacco leaves, the counterweight *p* is pivoted to the position *p'* (Fig. 2) and the springs *m* are thus removed to the position *m'* in the direction of the arrow *D* (Fig. 2). The leaves being introduced with their stems in the support the counterweight is brought in the operative position. The springs *l*, *m* and the counterweight *p* are adjusted so that, whatever the size of the stem may be, the latter always automatically lies in the central position in front of the aperture *i* of the support and the needle will perfectly pierce the stem in its middle portion.

When the needle *e* is at the end of its course after having pierced through the whole series of leaf stems, the string *f* is hooked on (Fig. 3) and the needle is retracted by winding in. The string drawn by the needle thus passes in the holes of all the stems and threading is completed.

To make it possible to vary the number of supports *b* in the threading apparatus and adjust the distance thereof between each other according to the thickness of the tobacco stems, said supports are mounted in a channelled guide *q*, and steadied therein by means of set screws *r* (Figs. 2 and 3).

I claim:

1. An apparatus for threading tobacco leaves comprising a base, a series of upright supports formed each by a rigid member and a resilient member between which the butt end of the leaf may be engaged, the rigid members having each an aperture in alignment over the whole series, resilient means in each support for holding the leaf stem in front of the aperture, a steel wire needle capable of running through the apertures while piercing the stems, and a rotary drum inside of which the needle can be wound and un-

wound so as to be reciprocated through the series of supports.

2. An apparatus for threading tobacco leaves comprising a base, a series of upright supports formed each by a rigid member and a resilient member between which the butt end of the leaf may be engaged, the rigid members having each an aperture in alinement over the whole series, a pair of blade springs arranged to be engaged by the butt end of the leaf stem for holding it in front of the corresponding aperture, means for adjusting the pressure of at least one of these blade springs, a steel wire needle capable of running through the apertures while piercing the stems, and a rotary drum inside of which the needle can be wound and unwound so as to be reciprocated through the series of supports.

3. An apparatus for threading tobacco leaves comprising a base, a series of upright supports formed each by a rigid member and a resilient member between which the butt end of the leaf may be engaged, the rigid members having each an aperture in alinement over the whole series, resilient means in each support for holding the leaf stem in front of the aperture, a steel wire needle capable of running through the apertures while piercing the stems, and a rotary drum with an offset guide and tangential entrance for winding and unwinding the needle in juxtaposed turns inside the drum.

4. An apparatus for threading tobacco leaves comprising a base, a channelled guide way on

said base, a series of upright supports slidably mounted in said guide way, each support being formed by a rigid member and a resilient member between which the butt end of the leaf may be engaged, the rigid members having each an aperture in alignment over the whole series, resilient means in each support for holding the leaf stem in front of the aperture, a steel wire needle cable of running through the apertures while piercing the stems, and a rotary drum inside of which the needle can be wound and unwound so as to be reciprocated through the series of supports. 5

5. An apparatus for threading tobacco leaves comprising a base, a series of upright supports formed each by a rigid member and a resilient member between which the butt end of the leaf may be engaged, the rigid members having each an aperture in alinement over the whole series, a lower blade spring arranged to sustain the butt end of the leaf stem, an upper blade spring for pressing said butt end against the lower spring, said upper springs forming a unit over the whole series of supports, which is pivotally mounted upon a common shaft and loaded with a counter-weight, a steel wire needle capable of running through the apertures while piercing the stems and a rotary drum inside of which the needle can be wound and unwound so as to be reciprocated through the series of supports. 15 20 25 30

PAUL MULLER.
